CLAIM

The ornamental design for a tool handle connector, as shown and described.

DESCRIPTION

FIG. 1 is a top, front and left side perspective view of a tool handle connector showing our new design;

FIG. 2 is a front elevational view thereof, the rear elevational view being a mirror image thereof;

FIG. 3 is a right side elevational view thereof with the left side being a mirror image thereof;

FIG. 4 is a top plan view thereof; and,

FIG. 5 is a bottom plan view thereof.

The handle and tool head shown in broken lines in the drawings is for illustrative purposes only and forms no part of the claimed design.

FIG.1

FIG.2

FIG.3

FIG.4
